UNITED STATES PATENT OFFICE

2,514,032

SLEEPING CAR FACILITIES

Albert G. Dean, Narberth, and Norman W. Fesmire, Willow Grove, Pa., assignors to The Budd Company, Philadelphia, Pa., a corporation of Pennsylvania

Application March 17, 1945, Serial No. 583,261

3 Claims. (Cl. 5—136)

1

This invention relates to sleeping car facilities, particularly to a folding bed and related devices, and has for an object the provision of improvements in this art.

One of the particular objects is to provide a power operated bed.

Another object is to provide safety means in connection with a power operated bed.

Another object is to provide power latch means for the bed, which latch means is operated whenever the bed actuating means is operated.

Another object is to provide interlocks providing that a basin and hopper cover are cleared when the bed is lowered adjacent thereto.

Another object is to provide convenient manual means for operating the bed independently of the power operating means.

The above and other objects of the invention will be apparent from the following description of an illustrative embodiment, reference being made to the accompanying drawings, wherein:

Figure 1 is a vertical longitudinal section through a few adjacent compartments;

Figure 2 is a vertical transverse elevation and section looking toward the bed in folded position;

Figure 3 is a broken vertical longitudinal section taken on the line 3—3 of Figure 2;

Figure 4 is a longitudinal section through the bed latching means, the section being taken on the line 4—4 of Figure 3;

Figure 5 is a section through the bed operating power connection, the section being taken on the line 5—5 of Figure 3;

Figure 6 is a vertical transverse section taken on the line 6—6 of Figure 1;

Figure 7 is a vertical section to show latch operating mechanism, the section being taken on the line 7—7 of Figure 3;

Figure 8 is a wiring diagram;

Figure 9 is a section in more detail of parts shown at the top of Figure 6, these parts being the basin interlock; and

Figure 10 is a vertical transverse section to show the hopper seat interlock.

Figure 11 is a diagrammatic sectional plan view, on a reduced scale and with detail omitted, of a room with the bed in lowered position, the section being taken substantially along the line 11—11 of Figure 6.

As shown in Figure 1, compartments 1, 2 and 3 are provided on one side of a coach 4. A window 5 is provided for each compartment. A bed 6 is hinged in one end of each compartment. For convenience in removal the hinge pins 7 of the bed are held in slotted brackets 8. A seat 9 is mounted in front of the bed and the back

2

10 of the seat is hinged to fold down when the bed is swung down. In compartment 2 the bed and chair back are shown in lowered position and in compartment 3 they are shown in raised position. The end support for the bed in lowered position is shown at 11. Means are provided for latching the bed in both raised and lowered positions and this mechanism will be described later. A baggage shelf 12, a mirror 13, and a bed lamp 14 are also shown in Figure 1.

This general arrangement of sleeping compartments is disclosed and claimed in an application Serial No. 583,259, filed of even date here-with, in the name of John W. Patton and entitled Sleeping Car.

As shown in Figures 6 and 11, a basin 17 is hinged at 18 on the aisle side of the compartment and a toilet 19 located at the end opposite the seat end is provided with a cover 20 hinged at 21 on an axis 21 (Figure 10). As will be explained later, interlocking means are provided for assuring that the basin and the toilet cover are closed before the bed is operated.

Power means are provided for operating the bed between lowered and raised positions. As shown this power means comprises an electric motor M mounted under the head end of the bed in such position as to partly balance the weight of the longer end. One or more springs 22 complete the balancing of the bed. Each spring is secured at the lower end to a fixed anchorage 23 and at the other end to a bracket 24 secured to the bed. One or both ends of each spring is so formed, for example as a hook, as to be quickly disengaged for removal of the bed.

As best shown in Figures 2, 3 and 5 the motor, provided with suitable speed reducing gears in its unit casing, operates a drive shaft 26, and this drive shaft operates the bed through relief means 40 which interrupts operation if an obstruction is encountered. This prevents injury to occupants of the compartment and also to the motor or equipment, the motor simply continuing to turn against yielding resistance if current is maintained too long. The operating means here illustrated is a friction drive and comprises a friction disk 27 secured on the motor shaft 26 between friction clamp discs 28 turnably mounted thereon, the disks 28 having arms 29 to which a reaction link 30 is pivoted at 31. The other end of the link is pivoted at 32 to a fixed bracket 33. The clamp disks 28 are resiliently held against the sides of the drive disk 27 by bolts 34, springs 35 and nuts 36. The motor reverses to move the bed in opposite directions.

The bed latching means includes a bolt or

plunger 40 carrying a roller 41 on its end, the roller being adapted in lowered position (Figure 3, compartment 1) to engage a keeper 42 in the end wall and in raised position (also Figure 3, compartment 2) to engage a keeper 43 in the top wall.

As best shown in Figure 4, the plunger 40 is slidably mounted in an opening of a guide 44 secured in the foot end of the bed and is adjustably connected by a rod 45 with a solenoid core 46 operated by a solenoid coil 47. In order to provide for selective operation by either power or hand the solenoid coil is mounted for longitudinal reciprocation, the casing 48 of the coil having an end member 49 which normally engages an abutment 50 to take the reaction of power operation. The solenoid core is pressed outwardly of the coil toward latching position by a spring 51 acting against another end member 52 of the solenoid casing. The outward movement of the core 46 is limited by a shoulder 53 thereon which engages the end member 49.

If power operation alone were concerned, the solenoid coil and casing could be fixed in position but for hand operation in case of current failure, it is desirable to have the coil and casing movably mounted and provided with means for manual movement. As here shown, an operating rod 55 is secured to the solenoid casing. As best shown in Figure 3, the operating rod 55 is slotted, as at 56, and connected to a pin 57 on a plate-like lever member 58 which is turnably mounted on a fixed pivot 59 carried by brackets 60 secured to the bed frame, Figure 7.

The member 58 may be operated either by hand lever 61 when the bed is in raised position or by a hand lever 62 when the bed is in lowered position. The lever 61 is mounted on a fixed pivot pin 63 and is operably connected to the member 58 by a link 64 and pins 65 and 66. The lever 62 is mounted on a fixed pivot pin 67 and is operably connected to the member 58 by a link 68 and pins 69 and 70. Operation of either hand lever 61 or 62 will operate the other but provision of the slot 56 in the rod 55 provides for movement of the levers from their extreme inward position before full pull to operate the latch is required to be exerted. This permits pull-out of flush type handles by the finger tips.

The hand levers, solenoid, and latch operating mechanism are all preferably mounted within the rail 71 of the bed which is located adjacent the aisle side where convenient for operation from the entrance door. Different ones of the two side rails will be used for mounting the latch means of the beds on opposite sides of the aisle. A spring 72 secured to the pin 65 of hand lever 61 and to a fixed bracket 73 on the bed frame holds both levers 61 and 62 and related parts in retracted position. As here located the spring 72 holds the hand levers 61 and 62 down but they may be held down by spring snap detents or the like to prevent rattling and then, by connecting the spring 72 directly to the rod 55 and to a fixed anchorage appropriately located, the hand levers may be initially moved without acting against the spring 72.

The latch operating mechanism is largely enclosed between the bed bottom shell and the inner shell 74 of the side rail 71. The shells 74 carry between them the mattress spring 75 to which is secured the mattress 76. The mechanism of the hand lever 62 is covered on the side by a short bent plate 77. The rail top edges are

covered by round edge finishing strips or by resilient upholstered edging if desired.

The bed operating motor and latch solenoid are controlled by a hand switch 80 (Figure 2) placed at some convenient location, as on the door side wall of a cabinet 79, which wall being located so near the door opening may be characterized as a door frame or jamb. By suitable means the switch may be held in central inoperative position unless held to one side or the other by hand.

As shown in Figure 9, the basin 17 is provided with snap latch means 81 for holding it in closed position. When closed it operates a switch 82, as by an arm 83. It may close an interlock switch in the present bed control circuit.

As shown in Figure 10 the cover 20 of the toilet 19 when closed operates an interlock switch 84, for example by closing it.

The control circuit is shown in Figure 8. Power current is supplied by lines L1, L2 to the switch 80 for the motor M and the latch-operating solenoid coil 47. The basin interlock switch 82 and the toilet cover interlock switch 84 are shown in one line, as L2, and until both are closed the current cannot be supplied to the bed operating motor M. Without explaining the circuit in detail, it can be seen that when the switch handle 80 is in upper position the motor M will be operated in one direction (as to raise) and when the switch handle is in lower position the motor will be operated in reverse direction (as to lower). In all cases the latch-operating coil is energized to withdraw the latch plunger.

In operation, assuming the bed to be located in its upper or stored position and the basin and toilet cover to be located in bed-clearing position with their interlock switches closed, the operator stands in the entrance door clear of the bed travel and moves the switch lever 80 downward. This releases the latch by action of the solenoid and starts the motor to lower the bed. If, after lowering, the switch is still held down the motor shaft will merely continue to turn against frictional resistance. When power is shut off the latch holds the bed. To raise the bed, the switch lever is moved and held in upper position until the bed is raised and latched. If during bed travel the switch is released the travel stops and the bed remains in this position until operated again.

The hand operation is obvious. If the bed is up the handle 61 is accessible and is operated; and if the bed is down the handle 62 is accessible from the door and is operated. Operation by hand against the friction drive connection is not at all difficult.

While one embodiment of the invention has been described by way of example, it is to be understood that there may be various embodiments within the limits of the prior art and the scope of the subjoined claims.

What is claimed is:

1. A bed comprising in combination, a bed frame mounted for movement between a stored and a usable position, power means for moving the bed between said positions, a latch for holding the bed in a position, operating means for the latch, means for controlling said power means to move the bed, and means activated by operation of said controlling means to actuate said latch operating means for release of said latch to permit movement of the bed.

2. Compartment facilities comprising in combination, a bed movable between use and stor-

age positions, a motor for so moving the bed, a wash basin located adjacent said bed and being movable between use and storage positions, the wash basin, in its use position, extending into the path of movement of the bed and, in its storage position, being disposed outside said path, and energizing means for said motor rendered unavailable by the wash basin in its use position but rendered available by the movement of the wash basin to its storage position, whereby motor-operation of the bed is prevented while the wash basin extends into the path of the bed.

3. Compartment facilities comprising in combination, a bed movable between use and storage positions, a motor for so moving said bed, an accessory element located adjacent said bed and movable between two positions, in one of which it extends into the path of movement of the bed and in the other of which it is disposed outside said path, and energizing means for said motor rendered unavailable by said accessory when the latter is in said one position but rendered available by the movement of the accessory to the other position, after which the bed may be motor-operated.
